(57) **CLAIM**

We claim the ornamental design for an electronic device ring, as shown as described.

DESCRIPTION

FIG. 1 is the front perspective view of an electronic device ring in accordance with the present invention.

FIG. 2 is the rear perspective view thereof.

FIG. 3 is the front view thereof.

FIG. 4 is the rear view of thereof.

FIG. 5 is the right side view thereof.

FIG. 6 is the left side view thereof.

FIG. 7 is the top view of thereof; and,

FIG. 8 is the bottom view of thereof.

The broken lines showing the remainder of a device ring in all views are directed to environment and form no part of the claimed design.

1 Claim, 6 Drawing Sheets
